UNITED STATES PATENT OFFICE.

THOMAS J. FAY, OF BROOKLYN, NEW YORK, ASSIGNOR, BY MESNE ASSIGNMENTS, TO THE STANDARD PARTS COMPANY, OF CLEVELAND, OHIO, A CORPORATION OF OHIO.

APPARATUS FOR HEAT TREATMENT OF STEEL.

1,249,056.

Specification of Letters Patent.

Patented Dec. 4, 1917.

Application filed July 9, 1914. Serial No. 849,916.

To all whom it may concern:

Be it known that I, THOMAS J. FAY, a citizen of the United States, residing at Brooklyn, in the county of Kings and State 5 of New York, have invented a certain new and useful Improvement in Apparatus for Heat Treatment of Steel, of which the following is a full, clear, and exact description, reference being had to the accompanying 10 drawings.

This invention relates to an apparatus for the heat treatment of steel and more especially of articles such as plates that are used in the construction of springs. The apparatus disclosed herein comprises generally a furnace (or a plurality of furnaces) wherein the plates—in the case of spring manufacturing—after having been cut to length and having the center holes punched therein— 15 may be heated for the ordinary forging operations which precede the heating of the plates for cambering and hardening purposes; the apparatus comprises also a construction and arrangement whereby the apparatus 20 sembed springs may be subjected to a drawing or annealing temperature (preferably by the waste gases from the aforesaid furnace or furnaces) and whereby this annealing or drawing may be accomplished simultaneously with the coating of enamel applied to the springs. In carrying out my invention, means are provided whereby the temperature will vary from end to end of each plate and whereby the temperature to which each plate 25 is subjected will vary with the amount of its immersion in a heated bath,—preferably of sand. It is a further object of the invention to provide a furnace wherein a bed of granular refractory material constitutes a bath 30 into which the article to be heated may be inserted and wherein the heat is so distributed throughout the furnace and applied to the bath as not to cake the refractory material and thereby interfere with the introduction of the articles thereinto.

With the foregoing objects in view the invention may be defined further and generally as consisting of the combinations of elements embodied in the claims hereto annexed and illustrated in the drawings forming part hereof, wherein Figure 1 represents a vertical sectional view corresponding to the line 1—1 of Fig. 3 and looking in the direction of the arrows; Fig. 2 represents a vertical sectional view corresponding to the line 2—2 of Fig.

1 and looking in the direction of the arrows; and Fig. 3 a view, partly in elevation and partly in section, the section through the right hand furnace corresponding to the line 3—3 of Fig. 1.

In the embodiment of my invention illustrated herein, two quadruple furnaces are shown the outlet flues whereof communicate with a common discharge duct, located therebeneath, and discharging into a flue extending beneath a tunnel. For convenience of description, it may be assumed that each quadruple furnace is a unit and, for economy of construction and efficiency in operation, it has been found to be desirable to construct 70 the furnaces in the manner illustrated and described herein.

1 denotes the top, 2 the side walls, and 3 the end walls of one of the furnaces referred to, said furnaces being particularly well 75 adapted for heating the ends of plates to permit of the various forging operations preliminary to cambering and hardening. Each wall 3 is provided with an opening 4, near the bottom thereof, communicating with the combustion chamber 5, said opening serving for the introduction of the combustible fluid—for instance, gas or oil mingled with air. A suitable burner, indicated at 6, is shown as projecting into each opening 4. 85 Each combustion chamber is preferably provided with a baffle 7 of refractory material located in such position as to be impinged upon by the entering fuel discharged from the burner. The combustion chambers 5 are 90 separated by a central wall 8.

Extending transversely across each combustion chamber 5 is an arch 9 of refractory material, and above said arch and extending tangentially with respect to the central portion thereof is a slab 10 of refractory material. With this arrangement, spaces 11 are provided between each slab 10 and the subjacent arch, each of which spaces is placed in communication with its respective combustion chamber through a suitable opening 9^a in each arch, said opening (where one opening is employed in each space) being located about half way between a central opening (employed in each space) being located 100 edge thereof. Extending upwardly from each combustion chamber is a pair of flues 12, said flues being located in the longitudinal wall 13 which extends the length of each unit and divides the same into two pairs of 110

furnaces. Each of the flues 12 communicates at its upper end with a pair of downwardly and laterally extending flues 14, said flues discharging the products of combustion 5 into the upper portions of the two furnaces 15 (the details of which will be described hereinafter) located above each combustion chamber and located on opposite sides of the wall 13.

- 10 The products of combustion, after circulating throughout the heating furnaces 15, above the sand bath therein, are discharged from the ends thereof. One of the discharge flues of each furnace 15 (see Fig. 2) 15 is provided in the wall 3, as indicated at 16, the products being discharged from a point near the roof of the furnace. The discharge from the opposite end of the furnace is through a downwardly inclined passageway 17 in the wall 13. A similarly arranged passageway 17 is provided for the adjacent furnace on the opposite side of the wall 13, and this pair of passageways merge into a common downwardly inclined flue 18, which flue 20 is itself inclined downwardly toward the central portion of the quadruple furnace, where it merges with a similar flue 18 which 25 conducts the gases from like points in the walls of the other adjacent pair of furnaces. The flues 18 merge into a common centrally 30 located down-flue 19 which communicates at its lower end with a transverse flue 20 located beneath the quadruple furnace. Each furnace 15 is provided with a flue 16 in the 35 end wall 3, there being four such flues for the quadruple furnace herein described. However, the flues 16 in each end wall 3, after extending downwardly a sufficient distance to clear the burner opening 4, merge 40 into a common centrally arranged down-flue 21, the flues 21 also discharging into the common discharge flue 20.

As will be evident from an inspection of Fig. 3, the two units, comprising eight furnaces, discharge their waste gases into the flue 20, said flue conducting the gases into a cross flue 22 the top whereof is covered by a plate 23 of cast iron or similar heat-radiating material. The top of this plate is provided with a trackway 24, and the space 45 above the plate is inclosed to provide a tunnel 25, the side and top walls 26 whereof are lined with non-heat-conducting material 27, the ends of the tunnel being closed by suitable doors 28, similarly lined to prevent heat 50 loss.

Each furnace 15 is located above a slab 10. It will be noted (see particularly Fig. 1) 55 that the lower part of each unit containing the combustion chambers 5 is of considerably greater width than the part thereabove. The outer lateral ends of the slabs 10 are at the bottoms of inwardly inclined surfaces 29 provided at the upper ends of the walls 28. These slabs, the inclined surfaces 29 of

the walls 2^a and the central wall 13 provide inclosures and supports for beds of granular refractory material 30, such as sand. Each furnace is provided with an opening 31 adapted to be closed by a sliding door 32 of suitable refractory non-heat-conducting material, which door is preferably provided with a beveled end 33, whereby it may enter the sand to a sufficient distance to form a seal therewith against the escape of the 75 products of combustion in the furnace 15. These doors are conveniently guided between channel-iron guideways 34.

The furnaces shown herein are especially designed for heating the ends of metal 80 plates, such as enter into the construction of springs, prior to the various forging operations, two of these plates being indicated at 35 and 36 (see Fig. 1). One of these plates is shown as resting on top of its wall 2^a and 85 has its inner end inserted into the sand beneath, and a short distance within, the bottom of the door 32. The other plate is shown as inserted to the maximum extent into the sand bed beneath the door 32. 90

It will be observed that a part only of each bath or bed of sand is subjected to the action of the heat within a furnace 15; in other words, the sand bath is heated at one end and is open to the atmosphere at the 95 other end. It follows, therefore, that the sand mass for each furnace varies in temperature from a maximum at the inner end (adjacent to the wall 13) to a minimum at the outer end (above the top of the inner 100 portion of the wall 2^a). It also follows that the temperature of any plate immersed in the sand will vary from a maximum at the inner end to a minimum at the outer end thereof and that this temperature in each 105 plate will itself vary in proportion to the depth the plate is immersed in the sand. For instance, the plate shown at the right hand of Fig. 1 is inserted substantially the maximum possible distance into the sand 110 with its inner end substantially in contact with the inner wall of the furnace which, in this case, is the middle wall between adjacent furnaces 15. The inner end of this plate will be heated thereby to the maximum 115 temperature possible, but the temperature in the plate will decrease from the inner toward the outer end thereof. The plate 35, which is shown as inserted about half the distance between the door 32 and the wall 120 13, will be heated to a correspondingly less 125 degree, not only as to its inner, or maximum-heated, end, but to a less degree throughout its entire length. It is proposed to use with each furnace a pyrometer inserted in the sand adjacent to the inner wall thereof—the central wall of the furnace assembly.

In the operation of a furnace constructed in accordance with my invention, the plates, being inserted into the furnace through the 130

exteriorly exposed surfaces of sand and beneath the doors 32 (which seal the exterior portion of the sand from the portion within the combustion chamber) are always sealed 5 from the products of combustion, whereby the overheating of the steel and the formation of scale are absolutely prevented. Furthermore, through this construction, there will be no necessity for the operator to open 10 and close doors, thereby realizing a great saving in time.

It is intended to use the products of combustion discharged from the furnaces 15 for the subsequent treatment of the plates, and 15 more especially for the purpose of drawing or annealing the springs in mass or assembled condition. For this purpose, the products are discharged into the transversely extending flue 22 and impart their heat to the 20 plate 23. The heat radiated from the plate 23 will raise the temperature within the tunnel 25 to a sufficient degree to anneal the assembled springs and do so without subjecting the springs (and the plates thereof) 25 to the direct action of the heating gases. The annealing of the springs in bulk will give superior results to annealing the individual plates for the following reasons:— The long or main plate should be a little 30 softer than the other plates; by annealing in mass, this result is secured because of the fact that the long plate is on the outside of the assembled plate and hence is subjected to a greater heating effect. The ends of the 35 short plates should also be a little softer than the other parts; this result is secured since these ends are freely exposed while the bodies are protected throughout the major portion of their length by their contact with 40 adjacent plates. The assembled springs are indicated at 35 on the truck 36.

In treating the springs in the tunnel 25 it is contemplated that, before subjecting them to the annealing operation, they will be 45 coated with enameling material. The temperature within the tunnel will serve, not only to anneal the springs, but to bake the enamel thereon and this operation is secured through the use of the waste gases from the 50 furnaces 15—a very important feature of my invention. The enamel with which the springs are coated serves to protect the steel during the annealing process and prevents any change in the percentage of the carbon 55 constituent thereof or in the carbon saturation. The apparatus disclosed herein is capable of and intended to be used in conjunction with that disclosed in my application No. 841,982, filed June 1, 1914 and 60 which cooperates therewith for the production of springs wherein the heating necessary for decalcification and the subsequent annealing is applied without subjecting the plates at any time to the licking of the 65 flames or to the direct action of the heat.

At no time during the treatment are the plates subjected to the direct action of the heat, thereby protecting them against molecular shocks. After the tempering heating, (which may be administered through 70 the style of the furnace disclosed in my prior application) the plates will be chambered through suitable mechanism, chilled, assembled, and annealed in assembled form as shown herein, the heat being applied to the 75 furnace throughout the production of the springs by the indirect method disclosed herein.

While the construction and process illustrated and described herein are designed 80 primarily for the treatment of plates which enter into the production of springs, it will be evident that the process and apparatus are capable of more general application. For instance, the action of the furnaces in 85 the progressive and proportional heating of the articles inserted therein will be the same with respect to any elongated articles capable of being thrust into the sand bath. It is obvious that rods are as capable of treatment in the furnaces shown herein as are plates. Hence, while, for convenience of description, specific reference is made to "plates" in the specification and claims hereof, I do not intend thereby to be limited in the uses of my invention nor to be 90 limited as to the specific articles treated thereby.

Having thus described my invention, what I claim is:—

1. In an apparatus of the character described, the combination, with a furnace chamber having means for supporting articles to be subjected to heat treatment, of means for supplying gases of combustion to 100 said chamber to heat such articles therein, a tunnel the bottom wall whereof consists of a plate of radiating material, said tunnel having a track therein and provided with doors and walls provided with non-heat-conducting material, and a flue beneath such heat radiating plate and receiving the gases of combustion from said chamber.

2. In a furnace, the combination of a combustion chamber and a heating chamber 115 thereabove, a slab interposed between said chambers, an arch for the combustion chamber beneath said slab, there being spaces provided between the slab and the lateral portions of the arch, said spaces being in 120 communication with the combustion chamber, and means for delivering gases of combustion from the first chamber to the second chamber at a point above said slab.

3. In a furnace, the combination of a combustion chamber, a heating chamber thereabove, a slab forming the bottom of the heating chamber and interposed between the same and the combustion chamber, an arch 125 for the combustion chamber supporting the 130

slab at its central portion and provided with openings placing the spaces beneath the lateral portions of the arch and the slab thereabove in communication with the combustion chamber, and means for delivering gases of combustion from the first-mentioned chamber into said heating chamber at a point above said slab.

4. In a furnace, the combination of a heating chamber, a bath of refractory granular material within said chamber and extending outside the same, and a gravity door for said chamber adapted to rest upon the granular material and seal the external portion thereof from the portion within the chamber.

5. In a furnace, the combination of a heating chamber, a bath of refractory granular material within said chamber and extending outside the same, and means for sealing the external portion of the mass of material from the portion within the chamber.

6. In a furnace, the combination of a heating chamber, a slab forming the bottom of said heating chamber and extending outside of said chamber, there being a bath of granular refractory material on said slab, and a vertically movable door carried by said furnace and having its lower end beveled whereby it is adapted to rest upon said bath and seal the external portion thereof from the portion within said chamber.

7. In a furnace, the combination of a heating chamber, a bath located partly within and partly without said chamber, and means for sealing the surface portion of the external part of said bath from the part within said chamber.

40 8. The combination, with a plurality of heating chambers, of a plurality of combustion chambers located beneath said heating chambers, there being flues conducting gases of combustion from the last mentioned chambers to the first mentioned chambers, a downwardly descending flue leading from each of the heating chambers, and a flue beneath the combustion chamber into which the first mentioned flues discharge.

50 9. In a furnace, the combination of a heat-

ing chamber, a combustion chamber located beneath said heating chamber, there being one or more flues conducting gases of combustion from the combustion chamber to the heating chamber, a bath of granular refractory material in the heating chamber beneath the flue connection or connections, and one or more outlet flues leading from the heating chamber and communicating therewith above said bath.

10. The combination, with a plurality of heating chambers and a plurality of combustion chambers therebeneath, of a pair of flues conducting gases of combustion from each combustion chamber to each heating chamber thereabove, each of the heating chambers being provided with a pair of outlet openings arranged in opposed walls thereof, downwardly extending flues communicating with said outlets, a flue beneath the combustion chambers with which the last mentioned flues communicate, and a heating space or chamber above and in operative relation to the last mentioned flue.

11. In a furnace installation, the combination of two pairs of combustion chambers and two pairs of heating chambers thereabove, the pairs of chambers being separated by an intermediate wall and each pair having a common outer wall, flues conducting gases of combustion from the combustion chambers into the heating chambers thereabove, each heating chamber having an outlet in the end wall and an outlet in the intermediate wall, the outlets of all four heating chambers in the intermediate wall communicating with a single downwardly extending flue and the outlets from each pair of heating chambers in an end wall communicating with a common flue in said wall, there being a flue beneath the combustion chambers with which the downwardly directed flues communicate.

In testimony whereof, I hereunto affix my signature in the presence of two witnesses.

THOMAS J. FAY.
